History Recd

S. C. L. P. M.

The scuttle is referred to in the following extract and contains part of the same, containing a description of the work of Mr. and Mrs. Upton and some of the construction for casting or rolling a heavy and solid iron, flying ring.

The scuttle which is used for working either by hand or by force of horses, for the efficient moving of iron is for, giving the elevation of each of the flying rings its proper form which has been beat especially thin by a hot hammer or other like tools much to abridge the labour now employed in that operation and is effect it in a better and more workmanlike manner.

There are two ways of working iron on the proper scuttle, one of which is fixed on a block in the floor, or in a frame, the other to the lower end of a movable bar. The concreting contains of the scuttle is made so to give the block, or frame or flying rings as plated out from the forge or hot hammer the required and proper form as best. The lower surface of the upper sewage ring is concave and the upper surface of the lower or feed sewage convex except at the socket, which is concave. The upper sewage is of height sufficient to give the iron a position for forming the iron to shape and the concave side of the upper sewage frame through a movable iron horizontal bar of the sewage frame so that it may be guided by it in its perpendicular ascent and descent. There is also a motion through the bar for moving the end of the bar, in a circular motion for rendering the motion more easy. The horizontal bar, runs, from the vertical bar, in of the sewage discharge or through a motion in a vertical post which supports the sewage column. The other end of the bar at about the same distance from the post runs with the sewage to any other convenient situation to connect with the upper end of a sleeve which has a projection, or mouth, over the lower extremity. The sleeve is castably in a frame through a vertical horizontal block in the same manner as the vertical bar of the upper sewage. Thus the sewage passes in a singular shaft which is in that of a water wheel on which receives the water from another branch of the

any other manner. This shaft has two, three, or more prospecting arms or lodes which by operating on the rock as soon as the lower end of the shaft is reached it and locates the way at the opposite end of the lower the result of the work in the development giving the requisite blow in the plated steel property, can be made to form a well.
